BELT SANDER

William B. Hickey, Denver, Colo.

Application December 6, 1937, Serial No. 178,242

7 Claims. (CL. 51—147)

This invention relates to improvements in belt sanders of the type employed in woodworking shops for sanding lumber.

It is common to subject lumber that is to be used for furniture and other purposes to a sanding operation for giving it a smooth surface that will take a fine finish and this is usually accomplished by means of a belt sander comprising a stationary frame having spaced pulleys mounted for rotation about parallel axes. One pulley is power driven and a sanding belt encircles the pulleys. The work is supported on an adjustable frame that is positioned underneath the sanding belt and which is movable transversely thereof and which is also vertically adjustable. Such sanders are very satisfactory but they are quite expensive and require a large amount of room.

It is the principal idea of this invention to produce a belt sander that is suspended from a frame in such a manner that it can be moved both transversely and longitudinally as well as vertically and which can also swing transversely. The work can be supported on carpenter horses or a movable table and even on the floor and the sander brought into position above the work. Such a sander is comparatively cheap to make and takes up very little room and is therefore especially well adapted for small cabinet and furniture shops, where both first cost and room are items of importance.

The belt sander that forms the subject of this invention comprises a suitable frame, usually constructed from wood, and which supports two pulleys which carry the sanding belt. The frame is extensible to permit the belt to be tightened or loosened. The frame is suspended from a track that extends transversely of the frame, by means that permits it to move transversely of the track and to swing transversely, means is provided for raising and lowering one end of the frame so as to adjust it with respect to the work.

Having thus briefly described the invention, the same will now be described in detail, and for this purpose reference will be had to the accompanying drawing in which the invention has been illustrated and in which:

Figure 1 is a top plan view of the sander;

Figure 2 is a side elevation, partly in section on line 2—2 Fig. 1;

Figure 3 is a section taken on line 3—3 Fig. 2; and

Figure 4 is a section taken on line 4—4 Fig. 2.

In the drawing reference numerals 5 designate two spaced parallel tracks supported at a suitable distance above the floor of a shop. Attached

to or forming part of members 5 are metal or wooden tracks 6. Suspended from the tracks 6 by means of track pulleys 7 of the kind employed with overhanging doors, is a rectangular frame 7a comprising sides 8 and ends 9. A shaft 10 is journaled in bearings 11 and is provided with a worm gear 12 that cooperates with a worm 13 on shaft 14. A crank 15 serves to turn shaft 14. Attached to the ends 9 are pulleys 16. Steel cables 17 are attached to the center drum section 18 of shaft 10 and have their ends attached to the upper frame member 19 by means of links 20. One of the cables 17 is provided with a turn-buckle 21 by means of which the sander can be tilted longitudinally.

If it should be found to be desirable to shift the sander in the direction of its length, the sides 8 may be provided with tracks 6 and a frame similar to frame 7a suspended from these tracks, all in a manner quite clear.

The sander frame, in addition to the upper frame member 19, already mentioned, has a frame member 22 and ends 23 and 24. A diagonal brace 25 connects the end 23 with upper frame member 19 and a similar diagonal brace 26 connects end 24 with frame member 22.

Referring now more particularly to Figs. 1 and 3 it will be seen that frame member 19 is provided with a dove tail slot 27 that extends to the end of the frame member. The sides forming the wall of the slot are connected by straps 28. Secured to the frame member 22 is a dove-tail strip 29 that cooperates with the inclined walls of the slot 27. It will be observed that the two frame members 19 and 22 are telescopically connected so that the length of the frame can be varied. The links 20 are both connected with the frame member 19. A rod 30 has one end secured in an opening in the end of frame member 22 and the other provided with an elongated nut 31. A threaded screw 32 passes through an opening in a metal plate 33, attached to members 19 and 23, and has a collar 34 that serves as a stop. A handle 35 serves as a means for turning the screw 32 for lengthening the frame.

Attached to the inclined braces 25 and 26 by suitable bearings and journals are pulleys 36 and 37 that are preferably but not necessarily of the same diameter. Pulley 36 has a grooved ring 38 attached to its outer surface and operatively associated with this ring is a belt 39 that transmits power from the pulley 40 of motor 41. Motor 41 is connected to a source of electric current by suitable flexible conductors that have not been shown as such connections are usual.

A sanding belt 42 is carried by the pulleys 36 and 37 and the tension of this belt can be adjusted by parts 38-35. A guy wire 43 has one end wrapped about shaft 10, as shown in Fig. 1, and after passing over a pulley 44 has its other end attached to the lower end of the guy wire at the left. This guy wire prevents the sander from swinging to any appreciable extent in the direction of the length of the sander. Although only one guy wire has been shown, it is obvious that two may be employed. The sander belt moves towards the right, as indicated by the arrow 45. A vertical guard is attached at its upper end to the diagonal brace 26 and extends downwardly in the manner shown. The object of this guard is to prevent the operator's hand or a tool from being moved into a position where it will be caught between the belt and the pulley 37.

The sander, which has just been described, can be moved to any position along track 5 and the latter may extend from one wall and therefore when the sander is not in use it may be positioned near that wall so as to be as much out of the way and to take up as little valuable space as possible.

The material to be sanded, and which has been designated by numeral 46, in Fig. 2, rests on the top of a suitable bench or table whose supporting surface has been designated by numeral 47. The supports 48 may be the legs of the bench, two saw horses, two boxes or any other supports, and it is not essential that the upper surface of the supporting surface 47 or the upper surface of the work be level, but it is preferable if it is. The work is positioned some place beneath the tracks 5 and preferably at right angles thereto. The sander is now moved along the track until it is directly over the work, after which the frame 1a is clamped so as to prevent its accidental movement. The crank 15 is now manipulated to lower the sander to a position in which the sanding belt will contact with the work, but in which the peripheries of the pulleys do not rest on the work. The motor is now started and the sanding belt is pressed against the work by a block 48 held in the hand of the operator. Block 48 is moved lengthwise of the belt and controls the rate of cutting. If the work is long, as in Fig. 2, it must be moved longitudinally to permit every part of its surface to be sanded. Where very long pieces are to be sanded, it may be desirable to employ another track at right angles to the first. If the work inclines in the direction of its length, the turn-buckle 21 is manipulated to give the same inclination to the sander. Any transverse inclination of the work is taken care of by a slight twist of the sanding belt.

Attention is called to the fact that the sander can swing transversely of frame 1a on account of the flexible suspension and this makes it possible to evenly surface a board that is much wider than the belt.

Owing to the flexible and the adjustable suspension of the sander, the work can rest on any convenient supports, and need not be carefully leveled. If an additional track is provided work of any length can be surfaced without being moved and work of any reasonable width can be surfaced because the sander can be moved along the track.

The track and the adjusting means are all parts of this invention, the same as if the adjustments were incorporated in a smaller and more compact machine.

The transverse swing movement of the sander is

important as it greatly facilitates the operation and the adaptability of the machine.

From the above it will be apparent that the machine described above illustrated on the drawing is very simple, can be built and installed at a comparatively small cost and does not need a complicated supporting device for the work. As a matter of fact, the lumber can be piled many layers deep on the supports and the upper layers surfaced and removed because the sander has a large vertical adjustment.

It is evident that the suspending means is reversible and such reversal is contemplated.

Having described the invention what is claimed as new is:

1. In a belt sander comprising in combination, a frame having two pulleys, mounted for rotation about spaced parallel axes, a sander belt on the pulleys, and power means connected with one pulley for turning it, a stationary work support positioned beneath the sander, a track positioned above the sander, a frame supported on the track for movement therealong, means for supporting the sander from the frame, said means comprising two cables connected with the sander at spaced points along its length, and means for adjusting the length of the supporting means to raise and lower the sander.

2. In a belt sander comprising in combination, a sander frame having two pulleys, mounted for rotation about spaced parallel axes, a sander belt on the pulleys and power means connected with one pulley for turning it, a stationary work support positioned beneath the sander, a track positioned above the sander, a frame supported on the track for movement therealong, means suspending the sander from the frame, said means comprising two cables connected with the sander at spaced points along its length, means comprising a drum for adjusting the distance from the frame to the sander, and means for changing the relative lengths of those portions of the cables between the supporting frame and the movable frame whereby the sander can be tilted in the direction of its length.

3. In a belt sander comprising in combination, a sander frame having two pulleys, mounted for rotation about spaced parallel axes, a sander belt on the pulleys and power means connected with one pulley for turning it, a stationary work support positioned beneath the sander, a track positioned above the sander, a frame supported on the track for movement therealong, a drum carried by one frame and mounted for rotation, means for rotating the drum, means for holding the drum against rotation after it has been rotated, two cables attached to the drum to be wound thereon, and pulleys attached to the frame, the cables passing over the pulleys, the free ends of the cables being attached to the sander for swingably supporting the latter.

4. In a belt sander comprising in combination, a sander frame having two pulleys, mounted for rotation about spaced parallel axes, a sander belt on the pulleys and power means connected with one pulley for turning it, a stationary work support positioned beneath the sander, a track positioned above the sander, a frame supported on the track for movement therealong, a drum mounted for rotation, means for rotating the drum, means for holding the drum against rotation after it has been rotated, two cables attached to the drum to be wound thereon, pulleys attached to the frame, the cables passing over the pulleys, the free ends of the cables being attached to the sander for

swingably supporting the latter, and means comprising a diagonal brace having its upper end connected with the supporting frame and its lower end connected with the sander frame for restraining the sander from swinging movement in the direction of its length.

5. In a belt sander comprising in combination, a sander frame having two pulleys, mounted for rotation about spaced parallel axes, a sander belt 10 on the pulleys and power means connected with one pulley for turning it, a stationary work support positioned beneath the sander, a track positioned above the sander, a frame supported on the track for movement therealong, a drum carried 15 by one frame and mounted for rotation, means for rotating the drum, means for holding the drum against rotation after it has been rotated, two cables attached to the drum to be wound thereon, pulleys attached to the frame, the cables passing 20 over the pulleys, the free ends of the cables being attached to the sander for swingably supporting the latter, and means for restraining the sander from swing movement in the direction of its length, said means comprising a flexible tension 25 cable having one end connected with the drum, the cable passing over a pulley secured to the frame and having its other end connected with the sander at a point longitudinally spaced from the position of the pulley whereby the sander will be

restrained in its longitudinal movement in one direction.

6. Means for adjustably suspending a belt sander comprising in combination, a track, a frame supported by the track for movement therealong, a shaft extending transversely of the frame, a worm wheel on the shaft, a second shaft carried by the frame for rotation about its axis, a worm on the shaft for engagement with the worm wheel, a pulley at each end of the frame, and cables passing 10 over the pulleys, one end of each cable being attached to the shaft for winding thereon and the other ends extending downwardly for attachment to a belt sander.

7. Means for adjustably suspending a belt sander comprising in combination, a track, a frame supported by the track for movement therealong, a shaft extending transversely of the frame, a worm wheel on the shaft, a second shaft carried by the frame for rotation about its axis, a worm 20 on the shaft for engagement with the worm wheel, a pulley at each end of the frame, cables passing over the pulleys, one end of each cable being attached to the shaft for winding thereon and the other ends extending downwardly for attachment 25 to a belt sander, and a turnbuckle in one of the cables.
